YOSMITE NABONA AND WILLIAM B. CHAPMAN, OF EL PASO COUNTY, COLORADO

AIRPLANE LANDING FIELD AND REMOTE CONTROL MEANS THEREFOR

Application filed April 12, 1930. Serial No. 443,762.

Our invention relates to landing platforms for the airplanes and our objects are to provide a rotatable platform device which can be located on the roof of a building or other 5 substructure; to provide a remote control apparatus which can be located on a nearby building or other structure; to provide means whereby the remote control apparatus can be operated automatically or manually; to provide a series of electro-magnets on said rotatable platform; to provide a device carrying a shoe, having magnetic properties, to coact with said electro-magnets, said shoe device having facilities whereby it may be attached 10 to the fuselage of an airplane. Other objects 15 will appear as the description progresses.

Figure 1 represents an elevation of the devices showing an airplane landed on the platform; Fig. 2, a sectional plan view on the line 2—2 in Fig. 3; Fig. 3, a sectional elevation of the device on the line 3—3 in Fig. 2; Fig. 4, a fragmentary sectional plan view on the line 4—4 in Fig. 3; Fig. 5, a fragmentary plan view showing the position of the poles 20 of the electro-magnets; Fig. 6, a side view of the device carrying the shoe 52; Fig. 7, a side view; Fig. 8, a plan view, parts of the shoe being broken away; and Fig. 9, a sectional elevation and plan view conduit 60 25 and brush assembly.

Although we show the preferred embodiment of our invention, we do not thereby limit ourselves to the precise form shown, but wish it understood that, within the scope of what 30 hereinafter is claimed, various changes in the details of construction may be made without departing from the spirit of the invention.

A circular track 1 is laid on a floor 2 supported by a substructure 3. Flanged wheels 4 run upon track 1 and are journalled on uprights 5 depending from a rectangular frame 6. A bevel ring gear 7 is secured to the underside of frame 6 and meshed with a bevel gear 8 mounted on a horizontal shaft 9 which is journalled in standards 10. A pulley 11 is mounted on shaft 9 and connected to a motor pulley 12 by a belt 13.

The landing platform comprises stringers 50 15 supported by frame 6, boards 16 secured

to stringers 15, and a mat 17 laid over boards 16.

A plurality of multi-polar electro-magnets 18 are mounted in said platform so that the poles extend upward flush with the tops of 55 boards 16.

A circular housing 19 is disposed on floor 2 concentric with circular track 1, and encloses a plurality of single pole electro-magnets A, B, C, D, E, F, G, and H arranged in a 60 circle concentric with track 1.

A series of lugs 20 depend from the top of housing 19, each lug being adjacent to an electro-magnet. A lever 20a is pivoted to each lug 20 and disposed so that one arm 65 extends across the pole of the adjacent electro-magnet and the other supports a pin 20b which is slidably disposed in a perforation in the top of housing 19.

A shaft 21 is mounted vertically in a base 70 22 located at a distance from the landing platform, as for example, on an adjacent building. An annular ring 23 is disposed on base 22 concentric with shaft 21.

Segmental plates a, b, c, d, e, f, g, and h, 75 separated by insulation 25, are disposed in a circle surrounding ring 23 and mounted on base 22, this base being provided with insulation 26. A housing 27 is rotatably mounted on shaft 21 and carries a vane 28. Insulation 80 29 is secured to housing 27 and carries a two pronged brush 30 which contracts with annular ring 23 and segmental plates a, b, c, d, e, f, g, and h. As shown diagrammatically in Fig. 2, electro-magnets A, B, C, D, E, F, G, 85 and H are connected, respectively, to segmental plates a, b, c, d, e, f, g, and h, by wires A1, B1, C1, D1, E1, F1, G1, and H1. Wires A2, B2, C2, D2, E2, F2, G2, and H2, connect wire K with electro-magnets A, B, C, D, E, 90 F, G, and H, respectively. Wires K and L lead to a source of electric current, as a generator G, wire L being connected to annular ring 23. The electro-magnets 18 are connected in series by wire M which leads to a source 95 of electric current as a generator G. A switch S is interposed in wire M and may be located conveniently for the operator.

Rings 30—31 are secured adjacent to insulation 32 which is secured to brackets 33, 100

bolted or riveted to frame 6. A horizontally swinging arm 34 is pivoted on terminal 35 which is connected to ring 31, and terminal 36 is connected to ring 30. A cylinder 40 is secured to stringer 15 by loop 41. A piston rod 42 is connected to insulation 39 on arm 34 and extends into cylinder 40. A piston 43 is mounted on the end of piston rod 42 within cylinder 40, and an open spring 44 is disposed about piston rod 42 adjacent to piston 43.

10 Brushes 45—46 are mounted on insulation 47 and contact with rings 30—31, respectively. Wires 48—49 lead from brushes 45—46, respectively, to the motor.

15 A device is attached to the fuselage 51 of an airplane, said device comprising a bracket 50; a shoe 52 secured to the bottom of said bracket; a shaft 53 mounted in lugs 54 on bracket 50; and a yoke 55 keyed on shaft 53 and carrying a wheel 56. A lever 57 is keyed on shaft 53 and connected to a lever 58 on the fuselage 51, by a rod 59.

20 The vane 28 being operated by the wind, swings the housing about the shaft 21 and moves the brush 30 over the segmental plates 25 *a, b, c, d, e, f, g, and h, and ring 23.*

25 If we assume that brush 30 is in contact with plate *g* at the time the switch *R* is closed, the electric current passes through ring 28, segmental plate *g*, wire *G1*, the coil in electro-magnet *G*, wire *G2* and wire *K* to the generator. The electric current energizes the electro-magnet *G* which attracts the adjacent lever *20a* and lifts a pin *20b* above the top of housing 19 and into the path of arm 34. When the motor *P* is started, the pulley 12 drives the belt 13 which turns the pulley 11 and actuates the gear 8 which engages the ring gear 7 and rotates the frame 6.

30 When the arm 34 strikes raised pin *20b* the action breaks the circuit between arm 34 and terminal 36, thereby stopping the motor and causing the frame 6 to stop. The position of the landing platform at this point is 35 parallel to the direction of the wind. The airplane, carrying the device which is provided with shoe 52, alights on the landing platform against the wind and therefore longitudinally of the platform. Before the airplane lands the pilot gives a signal and the 40 landing field attendant closes the switch *S* and permits the electric current to energize to magnets 18. As the shoe 52 is drawn across the poles of the magnets 18, it is attracted 45 thereby and gradually slows down the airplane until it comes to rest, which is accomplished before the shoe 52 has traveled the full length of the platform. If the remote 50 control apparatus becomes out of order, the attendant may control the position of the landing platform, by cutting off the power when the platform assumes the proper position relative to the wind. This is done by 55 opening the switch *R*.

55 A stationary platform 70 surrounds the

rotatable platform and is for the purpose of providing parking space for airplanes.

60 A vertically disposed conduit 60 is secured to frame 6 concentrically with housing 19 and provided with brushes 61—62 secured to lugs 63—64, respectively. Two ring terminals 65—66 are disposed concentrically with housing 19 and mounted on insulation 67 so that brushes 61—62 contact with ring terminals 65—66, respectively. A wire *M* 75 is connected to brush 61 and leads to switch *S*. A wire *M* is connected to brush 62 and leads to wire *C2*.

70 A catapult or other launching means may be mounted on platforms 17 or 70. 80

Having thus described our invention, what we claim as new and desire to secure by Letters Patent is:

1. In an airplane landing field, the combination of a floor adapted to be mounted on a substructure; a circular track laid on said floor; a horizontal frame, provided with uprights, disposed above said track; flanged wheels mounted on said uprights and disposed so as to run on said track; a horizontally disposed bevel ring gear secured to the underside of said frame; a pair of standards on said floor; a horizontally disposed shaft journalled in said standards and carrying a bevel gear meshed with said ring gear; a pulley mounted on said shaft; a motor; a belt mounted on said pulley and the pulley of said motor; a platform superimposed on said frame; a series of vertically disposed electro-magnets mounted in said platform with their poles upward; a wire from said electro-magnets leading to a source of electric current. 90

95 100 105 110 115 120 125 130

2. In an airplane landing field, the combination of a floor adapted to be mounted on a substructure; a circular track laid on said floor; a horizontal frame, provided with uprights, disposed above said track; flanged wheels mounted on said uprights and disposed so as to run on said track; a horizontally disposed bevel ring gear secured to the underside of said frame; a pair of standards on said floor; a horizontally disposed shaft journalled in said standards and carrying a bevel gear meshed with said ring gear; a pulley mounted on said shaft; a motor; a belt mounted on said pulley and the pulley of said motor; a platform superimposed on said frame; a series of vertically disposed electro-magnets mounted in said platform with their poles upward; a wire from said electro-magnets leading to a source of electric current; a mat covering the poles of said magnets.

3. In an airplane landing field, the combination of a floor adapted to be mounted on a substructure; a circular track laid on said floor; a horizontal frame, provided with uprights, disposed above said track; flanged wheels mounted on said uprights and dis-

posed so as to run on said track; a horizontally disposed bevel ring gear secured to the underside of said frame; a pair of standards on said floor; a horizontally disposed shaft 5 journalled in said standards and carrying a bevel gear meshed with said ring gear; a pair of concentric annular rings mounted on the underside of said frame, each ring being provided with a vertically disposed terminal: a contact arm pivoted on one of said terminals and adapted to contact with the other terminal; a pair of brushes mounted below said concentric annular rings, one brush contacting with the inside, and one 15 with the outside ring; a wire connecting each brush with a source of electric current.

4. In an airplane landing field, the combination of a floor adapted to be mounted on a substructure; a circular track laid on 20 said floor; a horizontal frame, provided with uprights, disposed above said track; flanged wheels mounted on said uprights and disposed so as to run on said track; a horizontally disposed bevel ring gear secured to the 25 underside of said frame; a pair of standards on said floor; a horizontally disposed shaft journalled in said standards and carrying a bevel gear meshed with said ring gear; a pair of concentric annular rings mounted on 30 the underside of said frame, each ring being provided with a vertically disposed terminal; a contact arm pivoted on one of said terminals and adapted to contact with the other terminal; a pair of brushes mounted below said concentric annular rings, one brush contacting with the inside, and one with the outside ring; a wire connecting each brush with a source of electric current.

5. In an airplane landing field, the combination of a floor adapted to be mounted on a substructure; a circular track laid on said floor; a horizontal frame, provided with 45 uprights, disposed above said track; flanged wheels mounted on said uprights and disposed so as to run on said track; a horizontally disposed bevel ring gear secured to the underside of said frame; a pair of standards on said floor; a horizontally disposed shaft journalled in said standards and carrying a bevel gear meshed with said ring gear; a platform superimposed on said frame; a series of vertically disposed electro- 50 magnets mounted in said platform with their poles upward; a wire from said electro-magnets leading to a source of electric current; a pair of concentric annular rings mounted on the underside of said frame, each ring being provided with a vertically disposed terminal; a contact arm pivoted on one of said terminals and adapted to contact with the other terminal; a pair of brushes mounted below said concentric annular rings, one brush contacting with the inside, and one with the outside ring; a wire connecting each brush 55 with a source of electric current.

6. In an airplane landing field, the combination of a floor adapted to be mounted on a substructure; a circular track laid on said floor; a horizontal frame, provided with up- 60

with the outside ring; a wire connecting each brush with a source of electric current.

6. In an airplane landing field, the combination of a floor adapted to be mounted on a substructure; a circular track laid on said floor; a horizontal frame, provided with uprights, disposed above said track; flanged wheels mounted on said uprights and disposed so as to run on said track; a horizontally disposed bevel ring gear secured to the underside of said frame; a pair of standards on said floor; a horizontally disposed shaft journalled in said standards and carrying a bevel gear meshed with said ring gear; a pair of concentric annular rings mounted on the underside of said frame, each ring being provided with a vertically disposed terminal; a contact arm pivoted on one of said terminals and adapted to contact with the other terminal; a pair of brushes mounted below said concentric annular rings, one brush contacting with the inside, and one with the outside ring; a wire connecting each brush with a source of electric current; a device to coat with said electro-magnets in said landing platform, said device comprising a bracket adapted to be attached to the fuselage of an airplane and a shoe attached to the bottom of said bracket. 70

7. In an airplane landing field, the combination of a floor adapted to be mounted on a substructure; a circular track laid on said floor; a horizontal frame, provided with uprights, disposed above said track; flanged wheels mounted on said uprights and disposed so as to run on said track; a horizontally disposed bevel ring gear secured to the underside of said frame; a pair of standards on said floor; a horizontally disposed shaft journalled in said standards and carrying a bevel gear meshed with said ring gear; a pulley mounted on said shaft; a motor; a belt mounted on said pulley and the pulley of said motor; a platform superimposed on said frame; a series of vertically disposed electro-magnets mounted in said platform with their poles upward; a wire from said electro-magnets leading to a source of electric current; a mat covering the poles of said magnets; a pair of concentric annular rings mounted on the underside of said frame, each ring being provided with a vertically disposed terminal; a contact arm pivoted on one of said terminals and adapted to contact with the other terminal; means to return said contact arm into contact and means to retard the return motion; a pair of brushes mounted below said concentric annular rings, one brush contacting with the inside, and one with the outside ring; a wire connecting each brush with a source of electric current. 75

8. In an airplane landing field, the combination of a floor adapted to be mounted on a substructure; a circular track laid on said floor; a horizontal frame, provided with up- 80
